DRAFT AND BUFFER GEAR

Stacy B. Haseltine, Chicago, Ill., assignor to W. H. Miner, Inc., Chicago, Ill., a corporation of Delaware

Application October 14, 1933, Serial No. 693,639

12 Claims.

(Cl. 213—9)

This invention relates to improvements in draft and buffering gears especially adapted for mine cars.

One object of the invention is to provide a simple and efficient combined draft and buffering gear, which may be economically manufactured.

Another object of the invention is to provide a gear of the character described in the preceding paragraph, which may be readily mounted on the end of a mine car and wherein simple and efficient means is employed for attaching the same to the end of the car, which means, when in operative position, also serves to limit the outward movement of the draft and buffering members of the gear.

Other objects of the invention will more clearly appear from the description and claims hereinafter following.

In the drawing, forming a part of this specification, Figure 1 is a horizontal sectional view of one end of a mine car, illustrating my improvements in connection therewith, said view being broken away and the section being on two different planes, and the improvements being shown in part plan and part horizontal section. Figure 2 is a part end elevational and part vertical sectional view, broken away, of the structure shown in Figure 1, the section being on the line 2—2 of Figure 1. And Figure 3 is a vertical sectional view, corresponding substantially to the line 3—3 of Figure 1.

In said drawing, 10 indicates one end of a mine car, 11 the vertical end wall, 12 the floor, and 13 an angle bar connecting the end wall 11 to the floor 12 and forming, in effect, the end sill member of the car.

My improved draft and buffering gear comprises broadly a draft member A; a pair of buffering caps B—B; a pair of shock absorbing springs C—C; a pair of combined retaining and stop bolts D—D; and a pair of guide castings E—E.

The draft member A is in the form of a transverse beam having spring cages 14—14 at opposite ends thereof. As most clearly shown in Figures 1 and 3, the spring cages 14—14 are in the form of casings which are open at their forward ends. The main body portion of the beam of the draft member A comprises a flat, platelike section 15 connecting the spring cages 14—14 and a forwardly projecting, central web 16, which has the midsection thereof thickened, as indicated at 17. The thickened portion 17 extends beyond the front edge of the web 16 and is formed with a vertical opening 18 adapted to accommodate a coupling pin. The rear end portion of

each spring cage 14 is closed by a vertical wall 19 having a central opening 20 therethrough. The wall 19 is offset forwardly with respect to the section 15 of the draft member and is provided with an annular, rearwardly projecting flange 21, which surrounds and reinforces the opening 20 of said wall 19.

The buffering caps B—B, which are disposed at opposite sides of the mechanism, are of like design. Each cap has a transverse front wall section 22, which presents a curved outer buffering surface 23 adapted to cooperate with the buffering cap of an adjacent car. The wall 22 has a rearwardly projecting, annular flange 24 thereon, which telescopes over the outer end of the spring cage 14 at the corresponding side of the gear. Centrally of each buffering cap B is a rearwardly projecting, hollow boss 25 adapted to accommodate the head of the corresponding combined retaining and stop bolt D, as hereinafter more clearly described.

The shock absorbing springs C—C are disposed at opposite sides of the mechanism and are accommodated within the spring cages 14—14. The rear ends of the springs C—C bear 25 on the rear walls 19—19 of the spring cages 14—14. At the forward ends, the springs C—C bear on radial webs 26—26 provided interiorly of the buffering caps B—B. The front ends of the springs C—C also bear on the inner ends of the bosses 25—25 of the buffering caps B—B, the bosses 25—25 being provided with annular shoulders for this purpose, as clearly shown in Figures 1 and 3.

The guide castings E—E are secured to the inner side of the end wall 11 of the car, as clearly shown in Figure 1. Each guide casting comprises a platelike section 27 having a forwardly projecting, sleevelike, hollow boss 28 thereon. The boss 28 extends through an opening 29 in the end wall 11 of the car and through the opening 28 of the end wall 19 of the corresponding spring cage 14 of the draft member A. The boss 28 is preferably of such a length as to engage within the coil of the corresponding spring C. Each guide casting E is also provided with a stop lug 30, which is spaced rearwardly from the platelike section 27 thereof and overhangs the opening of the sleevelike boss 28. The platelike section 27 of each guide casting is secured to the end wall 11 of the car by any suitable means, rivets being shown in the present instance.

The combined retaining and stop bolts D—D extend through the openings of the buffering caps B—B and the sleevelike bosses 28—28 of the guide castings E—E and have the heads thereof 55

in shouldered engagement with the inner end portions of the bosses 25—25 of the buffering caps B—B. The bolts D—D serve to hold the mechanism assembled and attached to the end of the car, each bolt being provided with a nut 31 at the inner end thereof for this purpose. The nuts 31—31 of the bolts have shouldered engagement with the platelike sections 27—27 of the castings E—E, thereby limiting the outward movement of said bolts. Inward movement of each bolt is prevented by engagement of the inner end thereof with the stop lug 30 of the corresponding guide casting E.

In order to prevent foreign matter from entering between the draft member and the end of the car when the draft member is in its outermost position, I provide an angle bar 32, which is secured to the end of the car and also serves to strengthen the end wall 11 of said car. As clearly shown in Figures 2 and 3, the flange 33 of the angle bar 32 is disposed in a horizontal plane and overhangs the inner end portion of the draft member A. The flange 33 is of such a width that it will at all times overhang the draft member so that foreign matter will be prevented from dropping between the draft member and the end wall 11 of the car. As will be evident, such foreign matter, if permitted to enter between these parts, would form an obstruction which would prevent the draft member from moving against the end wall of the car, thus decreasing both the draft and buffering strokes of the gear.

In mounting the combined draft and buffering gear on the end of the car, the guide castings E—E are first secured in position. The assembled parts comprising the draft member A, the buffering caps B—B, the springs C—C, and the bolts D—D may then be placed into position, the bolts being passed through the openings of the sleeve-like bosses 28—28 of the castings E—E. The nuts 31—31 are then secured to the bolts and locked in position by cotter pins 34—34 in the usual well-known manner.

The operation of my improved combined draft and buffering gear is as follows: When a pulling force is applied to the draft member A, the same is moved outwardly away from the car, thereby compressing the springs C—C against the buffering caps B—B, which at this time are held in fixed position by the bolts D—D. Outward movement of the draft member is limited by engagement of the front ends of the spring cages with the inner sides of the buffering caps B—B, thereby preventing undue compression of the springs C—C. In a buffering action, the buffering caps B—B are forced inwardly toward the end of the car, thereby compressing the springs C—C against the draft member A, which at this time is held stationary by engagement with the end wall 11 of the car. As clearly shown in Figures 1 and 3, sufficient clearance within the bosses 25—25 of the buffering caps B—B is provided to permit the required movement of the buffering caps without the heads of the bolts being projected beyond the buffering surfaces of said buffering caps. Inward movement of the buffering caps B—B is positively arrested by engagement with the outer ends of the spring cages 14—14 of the draft member A.

The bosses 28—28 of the casting E—E are of such a length that they extend through the draft member A in all operative positions of the latter and thus form effective guide means preventing lateral and vertical displacement of the draft member A.

75 I have herein shown and described what I now

consider the preferred manner of carrying out my invention, but the same is merely illustrative and I contemplate all changes and modifications that come within the scope of the claims appended hereto.

I claim:

1. In a draft and buffering gear for mine cars, the combination with a draft member having means for coupling the same to an adjacent car, said draft member having guideways at opposite ends thereof; of a buffering member, said draft and buffering members being movable toward and away from each other; spring means interposed between said members and having the front and rear ends thereof bearing respectively on said buffering and draft members; supporting means having guide lugs thereon extending through the guideways of said draft member; and attaching means extending lengthwise of the car through said buffering member and said lugs, said attaching means having shouldered engagement with the buffering member and car to limit outward movement of said buffering member.

2. In a draft and buffering gear for mine cars, the combination with a draft member normally bearing on the end of the car, said draft member having guide openings at opposite ends; of spring means bearing at the inner end on the draft member; a bracket secured to the end of the car, said bracket having cylindrical guide sleeves extending through the guide openings of the draft member; a buffering member bearing on the outer end of the spring means; and a retaining element disposed lengthwise of the car and extending through the guide sleeve and the buffering member, said retaining element having shouldered engagement at the inner end with the car to limit outward movement of said retaining element, said retaining element also having shouldered engagement at the outer end with the buffering member to limit outward movement of the latter.

3. In a draft and buffering gear for mine cars, the combination with a draft member extending transversely of and bearing on the end of the car; of shock absorbing means at opposite sides of the car bearing on the draft member; buffering means bearing on said shock absorbing means; and combined guide and retaining means disposed lengthwise of the car extending through the draft member and buffering means and comprising portions having shouldered engagement with the car to limit outward movement of said retaining means, said combined means including portions on which the draft member is slideable, said means also including head portions in shouldered engagement with the buffering means to limit outward movement of the latter.

4. In a draft and buffering gear for mine cars, the combination with a draft member extending transversely of the end of the car and normally bearing on said end; of shock absorbing springs bearing at their inner ends on said draft member; a pair of buffering caps at opposite sides of the car bearing on the outer ends of said springs; guide sleeves projecting from the end of the car and extending through the draft members; and retaining bolts extending through said springs, guide sleeves, and buffering caps, said bolts having shouldered engagement at opposite ends with said car and buffering caps to retain the draft and buffering gear in position on the car and limit outward movement of the buffering caps.

5. In a draft and buffering gear for mine cars, the combination with a supporting member on

the end of the car having forwardly extending cylindrical guide sleeves thereon; of a draft member extending transversely of the end of the car and normally bearing on said end, said draft member being slidably supported on said guide sleeves; a pair of buffering caps at opposite sides of the car, said caps being movable inwardly toward said draft member; shock absorbing means interposed between the draft member and buffering caps to yieldingly oppose relative movement thereof; and retaining bolts extending lengthwise of the car through said guide sleeves and buffering caps, said bolts being anchored to the end of the car and having shouldered engagement with the buffering caps to limit outward movement of the latter, said draft member having stop means thereon engageable with the buffering caps to limit outward movement of the draft member during a draft action of the mechanism and inward movement of the buffering caps during a buffering action.

6. In a draft and buffering gear for mine cars, the combination with a draft member extending transversely of the end of the car and normally bearing on said end, said draft member having forwardly opening spring cages at opposite ends thereof; of a pair of buffering caps telescoped over said spring cages and engageable with the front ends of said cages to limit relative movement of said draft member and buffering caps; springs within said cages bearing on the inner sides of said caps; a supporting member secured to the end of the car, said member having forwardly projecting cylindrical guide sleeves thereon, extending through the draft member and supporting the same for sliding movement and retaining elements anchored to the end of the car and extending through the buffering caps, the cages of the draft member, and the guide sleeves, said retaining elements having shouldered engagement with the buffering caps to limit outward movement of the latter.

7. In a draft and buffering gear for mine cars, the combination with a draft member normally bearing on the end of the car, said draft member having circular guide openings at opposite ends; of spring means bearing at the inner end on the draft member; a pair of buffering members bearing on the outer end of the spring means; guide sleeves forwardly projecting from the car and fitting within said guide openings of the draft member; retaining elements disposed lengthwise of the car and extending through the buffering members and said sleeves, said retaining elements having shouldered engagement at the inner end with fixed abutment means on the car to limit outward movement of said retaining elements, said retaining elements also having shouldered engagement at the outer ends with the buffering member to limit outward movement of the latter; and transversely extending bracing means fixed to the end of the car above said draft member, said means having a ledge overhanging the rear portion of the draft member to shield the latter.

8. In a draft and buffering gear for mine cars, the combination with a draft member having means for coupling the same to an adjacent car; of a buffering member, said draft and buffering members being movable toward and away from each other; spring means interposed between said members and having the front and rear ends thereof bearing respectively on said buffering and draft members; attaching means extending lengthwise of the car through said draft and

buffing members, said attaching means having shouldered engagement with the buffering member and car to limit outward movement of said buffering member; and a supporting bracket for said attaching means, said bracket being fixed to the end of the car and having means thereon in shouldered engagement with the attaching means to hold the latter against inward movement. 5

9. In a draft and buffering gear for mine cars, 10 the combination with a draft member normally bearing on the end of the car; of spring means bearing at the inner end on the draft member; a buffering member bearing on the outer end of the spring means; a supporting bracket fixed to the 15 end of the car; and a retaining element disposed lengthwise of the car extending through the draft and buffering members and said bracket, said retaining element having shouldered engagement with said bracket to retain said element against 20 inward and outward movement, said retaining element having shouldered engagement at the outer end with the buffering member to limit outward movement of the latter.

10. In a draft and buffering gear for mine cars, 25 the combination with a draft member extending transversely of and bearing on the end of the car; of shock absorbing means at opposite sides of the car bearing on the draft member; buffering means bearing on said shock absorbing means; 30 supporting brackets fixed to the end of the car, each bracket having an abutment ledge thereon; and retaining elements disposed lengthwise of the car extending through the draft member, buffering means, and brackets and having their 35 inner ends abutting said ledges of the brackets, said retaining elements having shouldered engagement with the brackets to limit outward movement of said elements, said elements also having heads at their outer ends in shouldered 40 engagement with the buffering means to limit outward movement of the latter.

11. In a draft and buffering gear for mine cars, the combination with a draft member extending transversely of the end of the car and normally 45 bearing on said end; of shock absorbing springs bearing at their inner ends on said draft member; a pair of buffering caps at opposite sides of the car bearing on the outer ends of said springs; brackets fixed to the end of the car, said brackets 50 having forwardly projecting bosses extending through the end of the car; and retainer bolts extending through said springs, draft member, caps, and bosses of the brackets, said bolts having shouldered engagement at opposite ends with 55 said brackets and buffering caps respectively to retain the draft and buffering gear in position on the car and limit outward movement of the buffering caps.

12. In a draft and buffering gear for mine cars, 60 the combination with a draft member extending transversely of the end of the car and normally bearing on said end, said draft member having forwardly opening spring cages at opposite ends thereof; of a pair of buffering caps telescoped over 65 said spring cages and engageable with the front ends of said cages to limit relative movement of said draft member and buffering caps; springs within said cages bearing on the inner sides of said caps; a pair of supporting brackets fixed 70 to the end of the car, each bracket having a platelike section provided with a forwardly projecting, hollow boss extending through the end of the car, each bracket also having a stop lug thereon spaced rearwardly from said platelike 75

section thereof, said stop lug overhanging the opening of the boss; and retaining bolts extending through said buffing caps, cages of the draft member, and bosses of the brackets, each bolt having a head at the outer end and a nut at the inner end, the heads of said bolts having shouldered engagement with the buffing caps, the nuts

of said bolts being confined between the plate-like sections and the lugs of the brackets, and the inner ends of the bolts being overlapped by said lugs and held against inward movement by engagement with the latter.

STACY B. HASELTINE.
